R. H. MacINNES

ELECTRIC STOVE INSULATING SUPPORT

Filed Aug. 18, 1924

Inventor

ROBERT H. MACINNIS

Attorney

UNITED STATES PATENT OFFICE.

ROBERT H. MACINNES, OF HAMILTON, ONTARIO, CANADA, ASSIGNOR TO D. MOORE COMPANY, LIMITED, OF HAMILTON, CANADA.

ELECTRIC-STOVE INSULATING SUPPORT.

Application filed August 18, 1924. Serial No. 732,748.

To all whom it may concern:

Be it known that ROBERT H. MACINNES, a subject of the King of Great Britain, residing at Hamilton, in the county of Wentworth, and Province of Ontario, Canada, has invented certain new and useful Improvements in an Electric-Stove Insulating Support, of which the following is a specification.

10 This invention relates to electric stoves, hot plates, and other electric heating appliances.

This invention especially has reference to an insulating support or carrier bar for 15 electric heater resistance coils and to an insulating connecting element for such bars.

In the construction of electric heating devices it is common to provide a series of bars for supporting the helically coiled resistance wire. In some instances, as in the 20 heating element used on top of stoves, the arrangement is such that these supporting bars extend radially from a common center. In other instances, as in grilles, heating elements for ovens and the like these supporting bars are placed side by side in parallel 25 relation.

Usually special bars are used for each purpose and these bars are not, in many cases, 30 interchangeable so that the same bar cannot be used in the oven of an electric stove as is used for the so called top burners.

One important object of the present invention is to provide an improved form of 35 insulating bar which is adapted for use interchangeably in either the oven or the top portion of a stove, can be assembled for grilles, and in fact, is capable of acting as a unit in the construction of any different type 40 of device wherein resistance coils are used.

It is also common in electric stoves and other like devices to carry the heat coils either spirally in a circular heating element or transversely to the supporting bars from 45 one side to the other of a rectangular heating element.

A second important object of the present 50 invention is to provide a supporting bar wherein the bar is so arranged to provide a bar with coiled resistant wire in an alternately curved arrangement, each bar carrying its own unit of resistance coils.

The modern stove or other like devices is 55 commonly arranged for three degrees of heat, low, medium and high. To this end

the resistance of the heating element is tapped off at its ends and at a point intermediate its ends.

A third important object of the invention is to provide a special insulating sleeve for 60 use in connection with the improved bar whereby this tapping off of the coils may be readily effected and whereby the several units may be connected one to the other each tapped. 65

With the above and other objects in view as will be hereinafter apparent, the invention consists in general of certain novel details of construction and combinations of parts hereinafter fully described, illustrated 70 in the accompanying drawings and specifically claimed.

In the accompanying drawings like characters of reference indicate like parts in the several views, and: 75

Figure 1 is a side elevation of the improved insulating bar and showing the improved tube or conduit, the device being illustrated in the manner in which it is applied to a stove having metallic top. 80

Figure 2 is a top plan view of one of the bars as shown in Figure 1.

Figure 3 is a section on the line 3—3 of Figure 1.

Figure 4 is a section on the line 4—4 of Figure 1. 85

Each unit bar, as constructed in accordance with the present invention is provided with a base 10 having laterally extending flanges 11 and running longitudinally of the upper part on the base is a rib or web 12 provided with a series of openings 13 between which, on each side of the web are vertically disposed lugs, or bosses 14, these bosses and openings alternating and there being one more boss than opening as clearly shown in the figures of the drawings. The stove top is indicated at 15 and a bottom 16 is connected thereto by means of posts 17 and cotter pins 18. 95

In this bottom portion is a pair of plates 19 and 20 which are held apart at the middle, the plate 19 being bent downward at its periphery to rest on the plate 20. The plate 19 is provided with a suitable opening 21 105 for each of the insulating bars, the opening being of proper size to take in the base 10 with the flanges 11 projecting between the two plates 19 and 20 so that the bars are held in proper fixed position. At one end 110

the flanges 11 terminate short of the end of the base 10 so as to leave a rabbetted portion 22 at this end and in this rabbetted portion fits the base 23 of a T-shaped conduit member having a downwardly extending stem 24 provided with a vertically disposed pair of openings 25 between which, at its lower end, is a binding post or screw 26. These openings 25, when the conduit is in position, register with similar openings 27 formed in the base 10 at one end thereof. The resistance wire is indicated at 28 and, as is ordinarily the case, this wire is preferably wound in convolutions and is led alternately from 15 one side to the other through the openings 13, one end of the wire being brought down through one of the openings 27 and the corresponding opening 25 and connected to the binding post 26. The other end of the wire 20 may, if desired, be carried over to a second insulating bar and connected to the resistance of that bar or may be brought back and led down through the other openings 27 and 25.

25 In this manner any number of these supporting bars may be used in any desired arrangement. They may be placed radially about a common center and may be extended as far as desired by the use of two or more bars in alinement. Similarly, any desired extent of rectangular arrangement may be made by arranging the bars end to end in such number as desired and then using as many rows or lines as is necessary to properly cover the surface of the heater or stove.

There has thus been provided a simple and efficient device of the kind described and for the purpose specified.

It is obvious that minor changes may be 40 made in the form and construction of the invention without departing from the material spirit thereof. It is not, therefore, desired to confine the invention to the exact form herein shown and described, but it is 45 desired to include all such as properly come within the scope claimed.

Having thus described the invention, what is claimed as new, is:

1. A supporting bar for electric heating devices formed of refractory insulating material and having a base and a web extending longitudinally of the base, said web being provided on its sides with spaced lugs, and having openings for resistance coils between said lugs. 50

2. A supporting bar for electric heating devices formed of refractory insulating material and having a base and a web extending longitudinally of the base, said web being provided on its sides with spaced lugs, 60 having openings for resistance coils between said lugs, and flanges extending laterally from the side edges of the base. 55

3. A supporting bar for electric heating devices formed of refractory insulating material and having a base and a web extending longitudinally of the base, said web being provided on its sides with spaced lugs, having openings for resistance coils between 70 said lugs, flanges extending laterally from the side edges of the base, said base being rabbetted at one end and provided with a conductor opening extending therethrough, and a T-shaped conduit having a base portion fitting the rabbetted portion of the base 75 of the bar and provided with openings registering with the openings in the base of the bar. 65

4. A supporting bar for electric heating devices formed of refractory insulating material and having a base and a web extending 80 longitudinally of the base, said web being provided on its sides with spaced lugs, having openings for resistance coils between said lugs; in combination with a spirally 85 wound resistance wire forming a helix, said helix being led through the openings in the web and having the portions between said openings resting against the lugs between the respective openings. 90

In testimony whereof I have affixed my signature.

ROBERT H. MACINNES.
